CLAIM

The ornamental design for a bottle shaped display, as shown and described.

DESCRIPTION

FIG. 1 is a top view of the bottle shaped display illustrating the new design, the stippled shading represents a contrasting surface appearance from what is shown on the opposite side; FIG. 2 is a bottom view of the bottle shaped display illustrated in FIG. 1;

FIG. 3 is an elevational right side view of the bottle shaped display illustrated in FIG. 1 (the elevational left side view is a mirror image of FIG. 3);

FIG. 4 is a rear view of the bottle shaped display illustrated in FIG. 1; and,

FIG. 5 is a front view of the bottle shaped display shown in FIG. 1.
